Primary Examiner — Elizabeth A. Albert(74) *Attorney, Agent, or Firm* — Knobbe Martens Olson & Bear LLP(57) **CLAIM**

The ornamental design for a drawing device, as shown and described.

DESCRIPTION

FIG. 1 is a front perspective view of a drawing tool showing our new design.

FIG. 2 is a back perspective view thereof.

FIG. 3 is a bottom perspective view thereof.

FIG. 4 is a front view thereof.

FIG. 5 is a back view thereof.

FIG. 6 is a right side view thereof.

FIG. 7 is a left side view thereof.

FIG. 8 is a top view thereof; and,

FIG. 9 is a bottom view thereof.

The broken lines in the drawings represent portions of the drawing tool that form no part of the claimed design.
